(57) **CLAIM**

The ornamental design for a LED ceiling light, as shown and described.

DESCRIPTION

FIG. 1 is a front, right, and top perspective view of a LED ceiling light, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the LED ceiling light that form no part of the claimed design.

1 Claim, 8 Drawing Sheets
